DESIGN FOR A PROTECTIVE HEAD
COVERING

Barbara J. Boeringer, Minneapolis, Minn.

Application May 18, 1946, Serial No. 129,848

Term of patent 3½ years

(CL. D3—13)

To all whom it may concern:

Be it known that I, Barbara J. Boeringer, a citizen of the United States and residing in the city of Minneapolis, county of Hennepin, State of Minnesota, have invented a new, original, and ornamental Design for a Protective Head Covering, of which the following is a specification, reference being made to the accompanying drawing, forming a part thereof, wherein:

Fig. 1 is a side elevational view of a protective head covering, showing my new design as it appears with the netting concealed in the crown portion.

Fig. 2 is a similar view thereof as it appears with the netting in lowered position.

Fig. 3 is a front perspective view of the protective head covering shown in Fig. 1.

Fig. 4 is a similar view thereof as it appears with the netting in lowered position; and

Fig. 5 is a rear elevational view of the protective head covering shown in Fig. 1.

I claim:

The ornamental design for a protective head covering, as shown.

BARBARA J. BOERINGER.
